PYROMETER

Application filed December 20, 1928. Serial No. 327,223.

This invention pertains to recording instruments, and more particularly to pyrometers adapted for the control of heating units or the like.

It is well known that there are various devices adapted for temperature, heat or other conditions control in large furnaces, heating plants and the like, but such devices are usually very complicated due to the power necessary for operating mechanism incident to control such conditions. One form of such heat control device is the pyrometer, and in the pyrometer as well as in other control, it is of course desirable, where possible, to have a direct operation from the device itself, but it has not been practical before to commercially utilize direct operation from a pyrometer due to the large currents necessary to be handled, as there is arcing, especially in breaking contacts to shut off the current flowing to the heating plant, which arcing rapidly destroys the points of the switch control; or where valve, switch or the like operation is necessary, not enough power can be developed in conjunction with apparatus used in sensitive work.

In order to adapt the pyrometer for heavy-duty work, it must be made to fulfill two requirements; namely, continuous operation (on outgoing effect), and the power to operate a heavy control. There are some pyrometers on the market in which operation is continuous; that is, for instance, when the switch control is closed, it remains closed until it is reversed. The difficulty however with this form of pyrometer is that operation is directly off the pointer or index, and as the system is necessarily very delicate, such pyrometer does not have the power to operate heavy apparatus. Again, there are no pyrometers on the market in which operation is such that it is possible to get anywhere near the amount of power out of the control as is gotten in the device which is the subject-matter of the present application, even with those where power is sought to be obtained at the expense of continuous operation where in the switch once closed remains closed for only a very short period. On this account it is necessary to compensate for this movement

by the use of a special type of relay which will operate in the short period of time and keep the switch closed until the conditions are reversed. This is objectionable in that the complete device for the heat control is very complicated.

It is then desirable to obtain a device which is an improvement over one employing mere continuous operation and one which is powerful enough though operated from a sensitive pointer, and also to obtain a device which will be a combination of these features; that is, will operate from a very sensitive movement, yet at the same time will give great power, in fact, power as great as desired, and that without affecting the sensitivity, and at the same time the arrangement to be such that the effect of this power may be continuous on whatever mechanism it is desired to operate.

It is therefore an object of this invention to provide a control of the millivoltmeter, galvanometer or the like device type for recording or indicating and controlling conditions such as temperature of a heating medium or unit.

Another object is to provide a selective device whereby a predetermined temperature can be maintained constant at a point remote from said device.

Still another object is to provide a device for controlling temperature of heating plants, units or the like, the device being such that a plurality of adaptations are possible as well as unlimited power control.

Yet another object is to provide a pyrometer which is of continuous operation (on outgoing effect) and adapted for heavy duty switch, valve or the like operation.

A further object is to provide a pyrometer adapted for heavy duty temperature control which is mechanically controlled from the temperature or condition index.

Still further object is to provide a temperature control device operative from a very sensitive movement, yet one which gives continuous power effect and unlimited power.

Yet further object is to provide a device adapted to show and/or control any func-

tion which can have its value or characteristic determined.

An additional object is to provide a device for indicating and controlling conditions, the 5 operation of which must be very delicate and sensitive in order to give accurate determination.

Still additional object is to provide a control device for controlling and/or indicating 10 varying or constant conditions.

Another additional object is to provide a device adapted for condition control, said device being operated from any or a sensitive movement.

15 A further additional object is to provide a device of long life and universal application, and one which fulfills all requirements of manufacture and service.

Still further additional object is to provide 20 a device for controlling remote conditions, which device is automatic of operation.

Yet further additional object is to provide 25 a device for controlling remote conditions, which device is continuous in operation and is operated to automatically clutch and de-clutch with means for affecting said remote conditions to thereby maintain said conditions in predetermined status.

30 With these and various other objects in view, the invention may consist of certain novel features of construction and operation, as will be more fully described and particularly pointed out in the specification, drawings and claims appended hereto.

In the drawings, which illustrate an embodiment of the device and wherein like reference characters are used to designate like parts—

40 Figure 1 is a fragmentary sectional perspective elevation, more or less diagrammatic, of a pyrometer which is the subject matter of this invention; showing the clutch mechanism in operative position;

45 Figures 2 to 5 inclusive are diagrammatic representations of the depressor and associated mechanism, showing the relative positions thereof during various degrees of operation of the device;

50 Figure 6 is an enlarged elevation of a portion of the positive clutch device;

Figure 7 is a more or less diagrammatic elevation, showing the pyrometer adapted for heavy duty work, said pyrometer being used 55 to control an electrical switch connected to a furnace heating unit; and

60 Figure 8 is a more or less diagrammatic elevation, showing the pyrometer adapted for heavy duty work, said pyrometer being used to directly operate valves of a fluid furnace.

Referring first of all more particularly to Figures 1 to 6 inclusive, it will of course be understood that the pyrometer herein described is suitably housed as indicated in 65 Figures 7 and 8, and presents a scale 20 con-

veniently located and calibrated so that temperature or other conditions to be controlled may be read by reference thereto and to the pointer or index 22. Said pointer or index 22 is preferably movable with respect to said scale and is connected to a galvanometer, millivoltmeter or the like armature 24, mounted for oscillation, the same being connected through suitable conductors to a thermocouple associated with a furnace, heat 70 ing plant or the like, the index 22 being provided with a suitable counterweight 26 to balance the weight of the pointer to eliminate the effect of gravity so that said pointer will operate in any position. Yoke 28 is pivoted for 75 external control through means which may cooperate with the aperture 30, the pivot being preferably in alignment with the axis of the armature 24, said yoke being provided with depending arms 32 to which a depressor 34 and a holder 36 are pivoted as at 38. The holder may take the form of a supporting arm 40 pivoted to the yoke 28 as at 38, said arm 40 being provided with a member 42 adapted to overlie and normally contact the index or pointer 22 to maintain the same in fixed position with reference to the scale 20.

The arm 40 is provided with a pin or member 44 overlying the forwardly extending portion 46 of the depressor 34, said pin 44 being adapted to be engaged by the portion 46 on the upward movement of said portion to raise the member 42 out of engagement with the index 22. The end of the portion 46 is provided with an angularly disposed index 90 engaging portion 48, the same being so proportioned that it engages the pointer only within small limits, said portion 48 having an extension 50 so arranged as to prevent the depressor from falling off of the index after it is once engaged. The depressor pivoted at 38 is provided with a rearwardly extending arm 52 which is an extension of the arm 46. Said arm 52 is adapted to be contacted by one arm 54 of a bellcrank 56, said bellcrank being pivoted as at 58 and provided with a depending arm 60 having a cam engaging roller 62 pivoted thereto. The roller 62 engages a suitable cam 64 mounted on a shaft 65, said shaft being rotated by a power driven device 66 either directly or through suitable gearing 68. Said power driven device may take the form of a motor, turbine, Diesel engine, gas engine, clock or any other prime mover, and may be of either the continuous or intermittent type.

The shaft 65, which is a driving shaft and is associated with the driven shaft 66 preferably aligned with said driving shaft, is adapted to be intermittently connected therewith through clutch mechanism 68. The clutch 68 is of the positive type, and as shown consists essentially of a plate or supporting member 70 secured to the driving shaft. The plate member 70 extends radially from the 115 120 125 130

driving shaft 65 and has a hook member 72 pivoted thereto as at 74 at a point removed from the axis of the shaft 65, the ledge 76 of the hook facing away from the shaft 65.

5 A tripping member or lever 78 is pivoted to the plate at 80, the point 80 being on the opposite side of the axis of the driving shaft from the pivot point 74 of the hook 72, and the lever 78 is pivotally connected as at 82 to a link 84, the other end of which is pivoted as at 86 to the head of the hook 72, a spring 88 being secured to the pivot 82, and the plate 70 urging the pivot 82 toward the plate. It will be noticed that the pivot point 15 82 is within the straight line connecting the pivots 80 and 86 and toward the axis of the shaft 64 so that a positive locking connection is normally maintained for the hook 72. The hook 72 is adapted to have engagement with an arm 90 of the crank 92, which 20 is secured to the driven shaft so that when the ledge 76 of the hook 72 is in engagement with the crank 92, the driving shaft may impart rotation to the driven shaft.

25 A selector 94 is pivoted at 96 at a point adjacent the clutch plate 70 and slightly biased with respect to the shaft 65, the selector taking the form of a substantially triangular plate having a notched portion 98 30 adapted to straddle the shaft 65, the selector being provided with upper and lower pins 100 and 102 disposed to have cooperative engagement with the tripping lever 78 to operate the same to move the latch 72 to 35 an inoperative position to thereby disconnect the driving shaft from the driven shaft. The selector is also provided with a pin 104 extending toward and adapted to have operative engagement with the depending arm 60 40 of the bellcrank 56 to limit the movement thereof under certain conditions. A latch member 106 is pivoted as at 108 at a point adjacent the cam 64 and is provided with shoulders 110 and 112, shoulder 110 being 45 adapted to have cooperative engagement with a trip pin 114 disposed on the cam 64, and shoulder 112 being adapted to have locking engagement in a plurality of positions with the pin 104 disposed on the selector 94.

50 Referring to Figure 7, the pyrometer 200 in this case is adapted for heavy duty in that operation may be effected by means of a motor and reduction gear train 202. In this case an electric heating apparatus 204 is provided with a suitable thermocouple 206 connected through the conductors 208 with the pyrometer for indication of temperature conditions by means of the pointer or index 222 and scale 220. The operated shaft 266 is 55 provided with a crank arm 210 connected through the link 212 with one arm of a bellcrank 214 of the snap switch 216, the other arm 218 of the bellcrank being connected through resilient connection 201 with crank 60 65 203 operating the switch members or arms

205. The operation of the switch 216 with the toggle joint and spring arrangement gives a quick opening movement to the switch while the link 212 may move slowly. In this way, high power and high voltage 70 may be handled since any kind of a contactor device may be used, the same being placed in series between the source of supply 207 and the resistor 209 of the heating apparatus, suitable conductors 211 being used. In 75 operation then, actuation of the shaft 266 by the pyrometer serves to open and close the switch arms 205, disconnecting or connecting the source of supply 207 with the resistor 209, thereby controlling the temperature of the 80 heating apparatus 204.

Referring now to Figure 8, as before the pyrometer 300 is adapted for heavy duty work, employing the motor and reduction gear train 302. The gas or oil heating apparatus 304 is provided with a suitable thermocouple 306 connected to the pyrometer through the conductors 308. The thermal changes in this heating apparatus are effected through the fluid valves 301 and 303 for 90 controlling the flow of fluid to the injector 305. In this case, the shaft 366 is provided with the crank 310 having a link 312 operating the valves 301 and 303 through crank and links 307 and 309 and 311. 95

Referring again to Figures 1 to 6 inclusive, the actuation of the pyrometer per se for controlling various systems such as described above is as follows: As already pointed out, a thermocouple is connected through suitable conductors to operate the armature 24, which in turn operates the pointer 22, it being understood of course that when the holder member 40 is in contact with the pointer 22, said pointer cannot be moved, but when the holder member 40 is raised from the pointer, said pointer is free to be moved by the armature, said movement depending upon the conditions of the furnace or unit to be controlled. 100

Assuming that the power unit 66' is of 110 continuous operation, it will be noticed that said unit is connected through suitable gearing with the shaft 65, rotating same at a predetermined rate, rotation of this shaft causing rotation of the cam 64, in turn actuating the bellcrank 56 to move the arm 54 to move the depressor 34, movement of the depressor 34 serving to raise and lower the holder member 40 out of and into engagement with the index 22. 115

The index 22, it will be noticed, is oscillated through the armature 24 which in turn is controlled through connections, such as the connections 208, from a thermocouple, such as thermocouple 206, it being understood that the thermocouple is associated with the heating apparatus and is affected by the change of heat therein. Assuming that heat is being supplied to the furnace, yet the temperature is below that which is necessary so that heat 125 130

must continue to be supplied, the current controlling the armature 24 will cause the index 22 to move out of the path of movement of the depressor 34, in which case the rotation of the cam 64 will operate the bellcrank 56 and in turn the depressor so that the depressor will pass the index 22, such as shown in Figure 2. Under these conditions, the selector 94 will have been locked in its upper position 10 by the latch 106, the ledge 112 engaging the pin 104 of the selector.

Rotation of the cam by the shaft 65 will cause the pin 114 to raise the lock 106 so that the ledge 112 is rendered inoperative with respect to the pin 104 of the selector. The arm 60 of the bellcrank however will cause the selector to remain in upper position where the pin 102 of the selector is in the path of movement of the lever 78 of the clutch so that rotation of the clutch member 70 will cause the outstanding portion of lever 78 to contact pin 102, such as illustrated in Figure 3, thereby breaking the toggle, operating the link 84 to move the hook 72 to a position where it will 25 not engage the arm 90 of the crank 92 so that no rotation can be imparted to the driven shaft this operation continuing so long as the index 22 does not interrupt the movement of the depressor. It will be seen that rotation of the shaft causes latching and unlatching of the selector, causing the selector to remain constantly in its uppermost position. However, when the temperature is raised sufficiently, the index 22 will be operated to 30 move to a position where it will interrupt the movement of the depressor, such as shown in Figure 4, in which case the pin 114 on the cam 64 will engage the lock 106 to raise said lock to release the selector which up to this 35 time has been locked in its upper position, such as illustrated in Figures 2 and 3. The selector then being biased will be permitted to move to the position illustrated in Figure 4, as the depressor is interrupted so that the selector is not kept in its upper position, in 40 which case the pin 100 is disposed in the path of movement of a portion of the lever 78 and the pin 102 will be moved out of the path of the lever 78. 45 Movement of the driving shaft 65 will cause the latch 72 to engage the arm 90 of the crank 92 to rotate the driven shaft to thereby shut off or diminish the means for 50 controlling thermal changes to the heating apparatus. The shafts revolve until the lever 78 contacts the pin 100, as shown in Figure 5, whereby to declutch by releasing engagement between the latch 68 and the arm 90. 55 and this operation will continue, that is, there will be no engagement between the latch and the crank, until the temperature is lowered sufficiently so that the index no longer 60 interrupts movement of the depressor when the parts assume the position as illustrated in 65

Figure 2, the operation of which already has been described.

In Figure 5, it will be noticed that while the clutch is being rendered inoperative, the selector is locked by means of the latch 106 70 though on each cycle the latch is released, yet the biased position of the plate will prevent unauthorized movement of said selector, and there will be no movement of said selector as the depressor is not lowered sufficiently due 75 to the position of the index, to move the selector to the position illustrated in Figure 2. It is only after the temperature of the heating apparatus is lowered sufficiently to move the index out of the path of movement of the depressor that the selector is moved to its 80 upper position whereby the latch 72 engages the arm 90 to move the shaft 66 to turn on the heat control means. The arm 90 is moved to a position as illustrated in Figure 2, when the lever 78 contacts pin 102 to release the clutch to thereby complete the cycle of operation of the control.

It is to be understood that we do not wish to be limited by the exact embodiment of the device shown, which is merely by way of illustration and not limitation, as various and other forms of the device will of course be apparent to those skilled in the art without departing from the spirit of the invention 95 or the scope of the claims.

We claim:

1. In a control device, the combination of an operating shaft, an operated shaft, means for connecting said shafts including a clutch, 100 said clutch including links for disengaging said clutch, said links normally resisting de-clutching operation.

2. In a control device, the combination of rotary shafts, means for connecting said shafts, control means for determining the operation of said means for connecting said shafts, and mechanical means on one of said shafts for effecting operation of said control means. 105

3. In a control device, the combination of rotary shafts, a clutch for connecting said shafts, a member for operating said clutch to control the connection of said shafts, means operable by one of said shafts for controlling movement of said member, and sensitive means responsive to variations in a controllable medium for effecting operation of said last named means for operating said clutch in relation to said medium. 115

4. In a control device for regulating thermal conditions in heating apparatus and the like, the combination of an index movable by a galvanometer controlled by a thermocouple connection from said heating apparatus, a 120 holder for contacting said index to maintain said index in inoperative positions, an oscillatable depressor disposed adjacent said index, the path of movement of said depressor intersecting the path of movement of said in- 130

dex, a pin carried by said depressor engageable with said holder for moving said holder out of contact with said index, a rotatable driving shaft constantly operated by a prime mover, a cam on said shaft, a bellcrank disposed adjacent said cam and having an arm engageable with and following said cam, said bellcrank having another arm engaging with and actuating said depressor, a driven shaft axially aligned with said driving shaft and having a clutch member including a crank thereon, a cooperating clutch device carried by said driving shaft and including a radially disposed supporting member fixed to said driving shaft, a latch member pivoted to said supporting member at a point removed from the shaft axis, said latch member being disposed to have engagement with said crank, a lever member pivoted to said supporting member at a point removed from said shaft axis and so disposed that said shaft axis is between the pivot point of said lever and said latch member, a connection pivoted to said lever and said latch, the pivot point of said latch and lever being disposed within the line joining the pivot point of said lever and the pivot point of said connection and latch and contacting said supporting member whereby said latch may be positively locked in crank engaging position, a resilient member connected to said supporting member and the pivot point between said lever and connection whereby the latch member is urged to crank engaging position, a selector disposed adjacent said shaft and having members adapted to be disposed in the path of said lever member to thereby move the latch to inoperative position whereby the driving shaft is declutched from the driven shaft, said selector having a member engageable with the cam engaging arm of said bellcrank to control movement of said selector, a latch member for said last named selector member, a member on said cam for controlling said latch, connecting means between said driven shaft and thermal control means of said heating apparatus whereby when said index does not interrupt movement of said depressor the last named latch is tripped and the cam engaging arm of said bellcrank operates said selector so that the clutch is operative whereby the driving shaft operates the driven shaft to move the thermal control means to increase the thermal conditions of said heating apparatus until one of the first named members on said selector moves the clutch member to declutched position rendering the driven shaft inoperative to operate the thermal control means, operation of said thermal means remaining unchanged until the index is moved to interrupt movement of said depressor whereby the cam engaging arm of said bellcrank moves the selector to position whereby the clutch device is operative to connect said shafts whereby the thermal con-

trol means is moved to decrease thermal conditions until the index again is moved out of the path of said depressor.

5. In a control device for regulating thermal conditions in heating apparatus and the like, the combination of an index movable according to thermal conditions in said heating apparatus, a movable depressor disposed adjacent said index, the path of movement of said depressor intersecting the path of movement of said index, a rotatable driving shaft, means disposed on said shaft for operating said depressor, a driven shaft, a clutch device for selectively connecting said driving and said driven shafts, and a selector disposed adjacent said shaft and being operatively connected by said first named means whereby the driving shaft may be declutched from the driven shaft.

6. In a control device for regulating thermal conditions in heating apparatus and the like, the combination of an index movable according to thermal conditions in said heating apparatus, a movable depressor disposed adjacent said index, the path of movement of said depressor intersecting the path of movement of said index, a rotatable driving shaft, means associated with said driving shaft and depressor for moving said depressor, a driven shaft, a clutch disposed between said driving and said driven shafts for selectively connecting said shafts, a selector disposed adjacent one of said shafts and provided with means for selectively controlling the clutch, said selector being provided with a member controlled by said first named means to control the position of said selector, and a member controlled by said means for maintaining the selector in positions depending upon the position of said index.

7. In a control device for regulating thermal conditions in heating apparatus and the like, the combination of an index movable according to thermal conditions in said heating apparatus, a movable depressor disposed adjacent said index, the path of movement of said depressor intersecting the path of movement of said index whereby the position of said index determines the movement of said depressor, a rotatable driving shaft, means associated with said shaft and depressor for imparting movement thereto, a driven shaft for controlling thermal control means of said heating apparatus, connecting means between the said shafts for selective connection thereof, and means controlled by said first named means for controlling said connecting means between said shafts.

8. In a control device for regulating thermal conditions in heating apparatus and the like, the combination of an index movable according to thermal conditions in said heating apparatus, a movable depressor disposed adjacent said index, the path of movement of said depressor intersecting the path of move-

ment of said index whereby the position of said index determines the movement of said depressor, a constantly operating driving shaft, means associated with said driving shaft and said depressor for controlling movement of said depressor, a driven shaft for controlling thermal control means of said heating apparatus, a clutch device disposed between said shafts for selectively connecting said shafts, and means controlled by said first named means for controlling the operation of said clutch.

9. In a control device for regulating thermal conditions in heating apparatus and the like, the combination of an index movable according to thermal conditions in said heating apparatus, a movable depressor disposed adjacent said index, the path of movement of said depressor intersecting the path of movement of said index whereby the position of said index determines the movement of said depressor, a constantly operating driving shaft, means associated with said driving shaft and said depressor for controlling movement of said depressor, a driven shaft for controlling thermal control means of said heating apparatus, a clutch device disposed between said shafts for selectively connecting said shafts, and means operable according to the position of said index to control operation of said clutch.

10. In a control device for regulating thermal conditions in heating apparatus and the like, the combination of an index movable according to thermal conditions in said heating apparatus, a movable depressor disposed adjacent said index, the path of movement of said depressor intersecting the path of movement of said index whereby the position of said index determines the movement of said depressor, a constantly operating driving shaft, means associated with said driving shaft and said depressor for controlling movement of said depressor, a driven shaft for controlling thermal control means of said heating apparatus, a clutch device disposed between said shafts for selectively connecting said shafts, and means operable by said first named means depending upon the position of said index for controlling the operation of said clutch.

11. In a control device for regulating thermal conditions in heating apparatus and the like, the combination of an index movable according to thermal conditions in said heating apparatus, a movable depressor disposed adjacent said index, the path of movement of said depressor intersecting the path of movement of said index whereby the position of said index determines the movement of said depressor, a constantly operating driving shaft, means associated with said driving shaft and said depressor for controlling movement of said depressor, a driven shaft for controlling thermal control means of said

heating apparatus, a clutch device disposed between said shafts for selectively connecting said shafts, means operable by said first named means for controlling the selective operation of said clutch, and a member cooperating with said last named means for locking the same in operative positions dependent upon the positions of said index.

12. In a control device for regulating thermal conditions in heating apparatus and the like, the combination of an index movable according to thermal conditions in said heating apparatus, a movable depressor disposed adjacent said index, the path of movement of said depressor intersecting the path of movement of said index, a rotatable driving shaft, means disposed on said shaft for operating said depressor, a driven shaft, a clutch device for selectively connecting said driving and said driven shafts, and a clutch operating member for selectively clutching and de-clutching said clutch device.

13. In a control device for regulating thermal conditions in heating apparatus and the like, the combination of an index movable according to thermal conditions in said heating apparatus, a movable depressor disposed adjacent said index, the path of movement of said depressor intersecting the path of movement of said index, a rotatable driving shaft, means disposed on said shaft for operating said depressor, a driven shaft, a clutch device for selectively connecting said driving and said driven shafts, and a clutch operating member operated by said driving shaft for selectively clutching and declutching said clutch device.

14. In a control device for regulating thermal conditions in heating apparatus and the like, the combination of an index movable according to thermal conditions in said heating apparatus, a movable depressor disposed adjacent said index, the path of movement of said depressor intersecting the path of movement of said index, a rotatable driving shaft, means disposed on said shaft for operating said depressor, a driven shaft, a clutch device for selectively connecting said driving and said driven shafts, and a clutch operating member operated by said driving shaft and controlled by said index for selectively clutching and declutching said clutch device.

15. In a control device, the combination of a continuously operated driving shaft, a driven shaft, a clutch for positively connecting said shafts, said clutch including an arm carried by one of said shafts and a latch carried by the other shaft for interlocking with said arm, links for holding said latch in latching position, said links normally resisting unlatching of said latch.

16. In a control device, the combination of an operating shaft, an operated shaft, means for connecting said shafts including a clutch, said clutch comprising a member on one of

- 5 said shafts, a second member on the other of said shafts for engaging the first named member, and means normally holding said second member in clutching position and means for operating said means at any one of a plurality of selected positions to prevent clutching of said parts at the selected position. 70
- 10 17. In combination with a movable index, a constantly operated driving shaft, a driven shaft, means for positively connecting said shafts; said means including normally inter-engaging parts carried by said shafts, said parts normally biased to interengaging position, and means controlled by said index for controlling said connecting means to selectively effect operation of said driven shaft. 75
- 15 18. In combination with a movable index, mechanism including a member beating across the path of the index and adapted to be intercepted by said index in certain positions thereof, a driving shaft for operating said mechanism, a driven shaft, means for positively connecting said shafts and means controlled by the coaction and non-coaction of 80
- 20 said member and index for controlling the connecting means to selectively effect operation of the driven shaft. 85
- 25 19. The combination with a movable pointer and a member to be controlled in accordance with the deflection of said pointer, of means cooperating with said pointer in certain positions thereof, a driving means for operating said first named means, driven means connected with said member for controlling operation thereof, interlocking means between said driving and driven means and controlled by said first named means to selectively effect operation of said member. 90
- 30 20. In a control device, the combination of 95
- 35 an operating shaft, an operated shaft, clutch members carried by each shaft and normally in engaging position, a selecting member for declutching said clutching members and means operated by said operating shaft for holding said selecting member in position during the declutching operation. 100
- 40 21. In a control device, the combination with rotary shafts, of clutch members carried by said shafts and normally in clutching position, a selector having means for declutching said clutch members at a plurality of points in their travel, and means for holding said selector in a plurality of positions to effect declutching operation of the clutch to cause a partial revolution of the driven shaft. 105
- 45 22. A control device, having in combination, rotary shafts, clutch members carried by said shafts, and a plurality of means for cooperation with said members to declutch the same and arranged so that at least one of said means is always in position to declutch said members whereby one of said shafts makes only a partial revolution at each operation. 110
- 50 23. A control device, having in combination, a driven and a driving shaft, an arm 115
- 55 carried by one of said shafts, a clutch member carried by the other shaft, a latch on said member for engagement with said arm, a trip lever pivoted to said member and a link connecting one end of said trip lever and said latch, the pivot of said link and trip lever being normally to one side of a straight line between the pivot of the lever and the pivot of the link with the latch, and means for tripping said trip lever to retract said latch from its arm engaging position. 120
- 60 24. In a control device, the combination of a continuously operated driving shaft, a driven shaft, a clutch member on each shaft, one of said members provided with an arm, the other of said member carrying a latch adapted to engage said arm and also carrying a lever and a link connecting one end of said lever and said latch, said lever and link normally resisting declutching action of the latch and a trip adapted to engage the free end of the lever to retract said latch and stop the driven shaft. 125
- 65 25. In a control device, the combination of an operating shaft, an operated shaft, an arm carried by said latter shaft, a clutch member carried by the other shaft and including a latch member adapted to engage said arm, a lever and a link connecting one end of the lever and latch and adapted to resist retraction of the latch, a trip member for cooperation with said lever to retract said latch to prevent engagement thereof with the arm, and means for holding said trip member in tripping position. 130
- 70 26. A control device, having in combination, two revolvable shafts, clutch members carried by each shaft and normally in clutching position, and including a trip lever for declutching said members, a selector provided with a plurality of arms for engagement with said trip lever to selectively trip said lever whereby said driven shaft is rotated only a partial revolution at each operation, a latch for holding said selector in tripping position and means operated by said driving shaft for releasing said latch whereby said selector is freed to take up a tripping position. 135
- 75 27. A control device, having in combination, two revolvable shafts, clutch members carried by each shaft and in clutching position, and including a trip for declutching said members, a selector provided with arms disposed on opposite sides of one of said shafts and so arranged that the trip engages one or the other of said arms at each revolution to cause a partial revolution of one of said shafts, and means for holding said selector in one or the other of its tripping positions, said latter means operated by one of said shafts and adapted to release said selector when the trip is intermediate said arms and to reengage and hold it in tripping position. 140

28. A control device, having in combination, an index responsive to variations in the value of a quantity to be controlled, a member cooperating with said index and controlled thereby, a driving shaft for operating said member, a driven shaft, clutch members carried by said shafts and normally in clutching position including a tripping lever carried by one of said members, a selector provided with a plurality of arms, at least one of which is disposed in position to trip said trip member to disengage said clutch members to cause a partial revolution of the driven shaft, operating means for the selector whereby its position is determined by said first named member, means for holding said selector in one or the other of its positions, and means operated by said driving shaft for momentarily releasing said holding means to permit said selector to take up a position in accordance with the position of said first named member whereby the operation of the driven shaft is selectively controlled. 70
29. In a control device, the combination of rotary shafts, cooperative clutch members carried by said shafts, a selector provided with means for operating said clutch members at points in the travel thereof, and means for selectively maintaining said selector in positions to effect operation of at least one of said clutch members whereby movement of one of said shafts is effected. 80
30. In a control device, the combination of rotary shafts, normally clutched cooperative clutch members carried by said shafts, a selector provided with means for declutching said clutch members at selected points in the travel thereof, and means for selectively maintaining said selector in positions to effect declutching operation of at least one of said clutch members whereby movement of one of said shafts is effected. 85
31. In a control device, the combination of rotary shafts, normally clutched cooperative clutch members carried by said shafts, a selector provided with means for declutching said clutch members at selected points in the travel thereof, and means for selectively maintaining said selector in positions to effect operation of at least one of said clutch members whereby movement of one of said shafts is effected. 90
32. In a control device, the combination of rotary shafts, normally clutched cooperative clutch members carried by said shafts, a selector provided with means for declutching said clutch members at selected points in the travel thereof, and means for selectively maintaining said selector in positions to effect declutching operation of at least one of said clutch members whereby a partial rotary movement of one of the shafts occurs. 100
33. In a control device, the combination of rotary shafts, normally clutched cooperative clutch members carried by said shafts, a selector provided with means for declutching said clutch members at selected points in the travel thereof, and means for selectively maintaining said selector in positions to effect declutching operation of at least one of said clutch members whereby a partial rotary movement of one of the shafts occurs. 105
34. In a control device, the combination of rotary shafts, normally clutched cooperative clutch members carried by said shafts, a selector provided with means for declutching said clutch members at selected points in the travel thereof, and means for selectively maintaining said selector in positions to effect declutching operation of at least one of said clutch members whereby a partial rotary movement of one of the shafts occurs. 110
35. In a control device, the combination of rotary shafts, normally clutched cooperative clutch members carried by said shafts, a selector provided with means for declutching said clutch members at selected points in the travel thereof, and means for selectively maintaining said selector in positions to effect declutching operation of at least one of said clutch members whereby a partial rotary movement of one of the shafts occurs. 115
36. In a control device, the combination of rotary shafts, normally clutched cooperative clutch members carried by said shafts, a selector provided with means for declutching said clutch members at selected points in the travel thereof, and means for selectively maintaining said selector in positions to effect declutching operation of at least one of said clutch members whereby a partial rotary movement of one of the shafts occurs. 120
37. In a control device, the combination of rotary shafts, normally clutched cooperative clutch members carried by said shafts, a selector provided with means for declutching said clutch members at selected points in the travel thereof, and means for selectively maintaining said selector in positions to effect declutching operation of at least one of said clutch members whereby a partial rotary movement of one of the shafts occurs. 125
38. In a control device, the combination of rotary shafts, normally clutched cooperative clutch members carried by said shafts, a selector provided with means for declutching said clutch members at selected points in the travel thereof, and means for selectively maintaining said selector in positions to effect declutching operation of at least one of said clutch members whereby a partial rotary movement of one of the shafts occurs. 130
